(57) **CLAIM**

The ornamental design for a bearing for a yo-yo, as shown and described.

DESCRIPTION

FIG. 1 is a front, top and right perspective view showing a first embodiment of our new design for a bearing for a yo-yo;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a reduced scale front view showing the first embodiment of the design in its intended context;

FIG. 9 is a front, top and right perspective view showing a second embodiment of our new design;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof; and,

FIG. 16 is a reduced scale front view showing the second embodiment in its intended context. The appearance within

(Continued)

the unshaded trapezoidal shaped areas in FIGS. 4 and 12 forms no part of the claimed design. The broken lines are included for the purpose of illustrating cross sectional views of a yo-yo and portions of the bearing for a yo-yo that form no part of the claimed design.

1 Claim, 14 Drawing Sheets
